Application July 28, 1934, Serial No. 737,342

10 Claims. (Cl. 229—37)

Our invention has reference to containers, preferably formed of paper, and more particularly intended for use in transporting and temporarily containing milk or other liquids, and which embody certain features of construction providing built-up containers having great rigidity and being absolutely proof against leakage.

Our invention further consists of features of construction which cooperate to provide a substantially rectilinear structure having strong angular sealing corners, and providing stability when positioned within a transporting carrier.

Our improved container further embodies a plurality of rectangular telescoping casings having overlapping sealed bottom closures resting one upon the other, the closure bottom of one of the casings also being of rectangular shape and having overlapping and interengaging perimetral edges to form a sealed union between the inner and outer casings.

Our improvements further embody a paper container having flexible top portions so folded and overlapped as to have opposite side edges resting one upon the other, and provided with slidable sealing means binding the overlapping edges in sealed contact and permitting the re-sealing of the container after a portion of the contents has been removed.

Our improvements also comprise a multi-ply paper container having inner and outer body portions of rectangular shape, one of said portions extending upwardly in a single-ply beyond the multi-ply body portion; and wherein further, the inner body portion has a separate inset bottom closure also of rectangular shape, while the outer body portion has creased and folded lower parts cemented to the bottom closure for positively sealing the bottom of the paper container.

Our improvements further embody features of construction which permit expansion of the contents within the containers responsive to atmospheric changes and without damage to the containers; and furthermore, because of their rectangular shape, the containers are permitted to be closely packed together in upright position within a carrier during transportation, thus preventing warm air circulating between the containers, whereby the contents of the containers are maintained cooler for a longer period than is possible with containers having other shapes.

With the above and other objects in view, the nature of which will be more fully understood from the following specification, the invention consists in the novel features of construction here-

inafter more fully described and defined in the claims.

Referring to the drawings: Fig. 1 is a perspective view illustrating our improved container in sealed condition as a finished product; Fig. 2 is a perspective view of the inner body portion forming part of our improved container; Fig. 3 is a perspective view of the bottom closure for the inner body portion of the container; Fig. 3a is a perspective view showing the bottom closure in attached position on the inner body portion of the container; Fig. 4 represents a sheet blank from which the outer body portion is formed; Fig. 5 is a perspective view showing the sheet corresponding to the outer body portion when in folded condition, and with the inner body portion telescoped therein; Figs. 6 and 7 are inverted perspective views showing the bottom of the outer body portion of the paper container in process of being formed; Fig. 8 is an inverted perspective view of the bottom of the outer body portion of the paper container in completed form; Fig. 9 is a perspective view of the slideable sealing means for the upper end of the paper container; Fig. 10 is a perspective view of a container embodying our improvements, but of a modified construction; Fig. 11 is a perspective view of the inset bottom closure portion for use in connection with the modified paper container; Fig. 11a is a perspective view of one end of the inset bottom closure of Fig. 11, in partial formation; Fig. 11b, is a perspective view of the end of the inset bottom closure of Fig. 11, in final form, and preliminary to insertion of the said closure into the outer body portion of the modified container; Fig. 12 is a perspective view of the inner body portion of the modified container, and having the flexible top walls; Fig. 13 is an inverted perspective view of the bottom of the outer body portion of the modified container, in process of formation; and Fig. 14 is an inverted perspective view of the completed bottom of the outer body portion of the modified container.

Fig. 2 represents the inner body portion of our improved container, and is formed of sheet material rectangular in shape and so creased and overlapped, as at 3, to form a rectangular box structure, but without top or bottom closures. The overlapped end portions 3 are cemented or glued together so as to make a rigid and sealed joint. At one end of this rectangular structure is secured a bottom closure portion 4, also of rectangular shape as shown in Fig. 3, said bottom closure being so creased and folded that, when it is inserted or secured to the bottom edges

of the body portion 2, it will form a tight sealed closure securely held in place by the flanged portions 5 which contact with and are sealed to the inner portion of the body part 2, while the secondary flange portions 6 contact with and are sealed to the outer portion of the body part 2, as shown in Fig. 3a.

After the bottom closure 4 has been glued or cemented in position in the bottom of the body portion 2, this part 2 is telescoped into the outer body portion 7, as shown in Fig. 5, and is of a size to snugly fit to the outer body portion 7 to which it is cemented or glued, and the container as a whole is finally subjected to a water-proofing operation with paraffin or equivalent wax-like materials.

As shown, the inner body portion 2 has a height considerably less than the outer portion 7, so that when the body parts 2 and 7 are interengaged, the lower part of the outer body member 7 extends below the inner body portion 2 to provide flaps or extensions 8 and 9; and also extends above the inner body part 2 to provide flexible walls 10 which may be creased inwardly and folded upon themselves to provide a sealed closure at the top of the paper container, said sealed closure being maintained in a closed condition by the employment of a sliding slotted tube 11 shown in Figs. 1 and 9. This tubular closure 11 may be slotted throughout its entire length and is preferably formed of spring metal, whereby it is provided with reasonable elasticity. Furthermore, the tubular seal is also preferably made tapering so that it may slide longitudinally and at the same time provide an increased clamping or sealing action when being slid into position. This metal sealing part 11 may act as a handle or means for more readily grasping the container and by which the container may be shifted without fear of disengagement during manual manipulation thereof.

Referring to Figs. 6 and 7, we have shown the container structure as inverted for more clearly illustrating the nature of the bottom thereof in process of being formed. At this stage of the construction, the flaps 8 and 9 are extended laterally and radially outward from the body portion 7 (of which they form a part) and the sealing closure 4. The flanges 5 and 6 of the bottom closure 4 provide rectangular strengthened walls 12 as a bottom foundation of the closure 4. These walls 12 provide a space 13 constituting a recess having reinforced bounding walls of multi-ply construction, being made up of the flanges 5 and 6 of Fig. 3, reinforced by the lower edges 14 of the inner portion 2. Furthermore, these bounding walls are additionally reinforced by the flap portions 8 and 9 (Fig. 6) of the outer body portion 7, when they are turned over the edge of the walls 12 and down into the recess 13 and glued to both the walls 12 and the bottom closure 4 constituting the closure for the inner body portion 2. This statement equally applies to the flaps 9 which are similarly bent or folded and glued in position upon the walls 12 and bottom closure 4, as shown in Figs. 6 and 7. In the case of the flaps 8, however, these are separately glued to the walls 12 and closure bottom 4, but in the case of the flaps 9, these are not only glued to the walls 12 and closure 4, but also to each other where they overlap, as shown at 15 in Fig. 8.

It will be observed that our improved containers are substantially rectangular in all directions and, therefore, aside from having a maximum

capacity for the space occupied, are of such shape that they may be closely packed in a transporting carrier and provide a minimum space intermediate of the containers for objectionable passage of air or gases, thus permitting the contents of the containers to be kept in cooler condition for a longer period without deterioration. Furthermore, it will be seen that the paper containers embodying our improved features are of a rigid and stable construction, due to the fact that the inner and outer body portions, including the intermediate inset bottom closure portion, are cemented or glued together and finally water-proofed as a whole, to insure a tightly sealed structure which is proof against leakage. It will also be seen that the inner and outer container bodies are so assembled that the container may be filled with liquid almost to the top and, at the same time, is provided with a detachable sealing means which, together with the employment of a more pliable paper outlet, enables the intermittent pouring of the liquid from the container to suit requirements and the re-sealing of the container to prevent contamination of the unused contents.

Furthermore, it will be seen that our improved container is of such construction that the overlapped portions 3 are at one side of the container while the overlapped portions 16 (see Fig. 5) are, in the finished construction, at the opposite side of the container, thus providing a balanced reinforcing of the walls of the inner and outer body portions of the container and thereby imparting strength and durability in a vertical direction. Moreover, it will be seen that while the flexible walls 10 are double-ply where the overlapped outer body portion 7 extends above the inner body portion, the remaining walls are single ply and consequently may be readily shaped to form a pouring lip at one side of the container and also permit easy application of the sliding sealing means 11 when initially sealing or re-sealing the container.

It will be understood from the description above that the several parts making up the containers and embodying our improvements may be easily and quickly stamped, embossed or otherwise prepared from sheet material to impart the rectangular box-like shape thereto, and with assurance of accurately positioning the parts relatively to each other. Furthermore, the construction is such that sanitary conditions are assured, especially as the shape and configuration of the parts making up the container permit the same to be built-up with a minimum handling of the paper or material entering into the structure.

Referring now to the modification of our paper container as shown in Figs. 10 to 14, inclusive, it will be observed that the general principle of construction of the container is similar to that shown in Figs. 1 to 9, inclusive, in that in both constructions there are inner and outer body portions, a separate inset bottom closure providing uniting means between the inner and outer body portions, and top flexible walls for temporarily sealing the container by use of the slidable sealing means of a construction similar to that shown in Fig. 9.

Referring more particularly to the details of the modified container structure, it will be seen that in this case the inner body portion 17 is provided with the top flexible walls 17a which are creased and folded in a manner similar to the flexible walls 10 of Fig. 5, and provided with the slidable sealing means 11 for sealing the con-

tainer. In this modification, it will be noted that the inner portion is open at the bottom and fits into and is glued or cemented to the inner walls of the inset bottom closure portion 18 of Fig. 11.

The inset bottom closure 18 of the modified container corresponds to the structure shown in Fig. 3, inasmuch as in both cases there is a continuous transverse bottom wall which is cemented to the bottom of the outer body portion, see Fig. 14 for example. More particularly referring to the construction of the modified inset bottom closure 18, the following features will be noted: A sheet of paper is folded at both ends, substantially as indicated in Fig. 11b to form a box-like structure (Fig. 11), the same resulting from the manner of folding indicated in Fig. 11a. This construction provides great rigidity to the walls of the container as a whole. As the inset bottom closure portion 18 is made of a single continuous sheet of paper so folded at each end that the box-like structure produced is continuous from the bottom up to the upper bounding edges without necessity for sealing any apertures, and provides a strong union between the inner and outer body portions 16 and 19 which is exceedingly liquid tight.

Referring now to the outer body portion 19 and more particularly as shown in Figs. 13 and 14, the same is formed of a sheet of paper folded in rectangular form and similar to what is shown in Fig. 8, but omitting the recess 15 therein. In the construction of the modified container of Figs. 13 and 14, the bottom is formed by folding the tabs on line 20 to provide the closures 21 facing each other and partly closing the bottom of the outer body portion. The tabs immediately connecting with the parts 22 in Fig. 13, constitute triangular portions which fold downward upon the bottom portions 21 and, at the same time, carry with them the extension of the side walls, indicated at 23, said walls being folded toward each other and substantially abutting along the line 24, as indicated in Fig. 14; or said parts may be extended to form an overlapped closure, as preferred. The parts 22 are glued or cemented to the parts 21 and substantially close the bottom of the outer body portion 19 of the container. When the outer body of the container is thus formed, it is strengthened by the insertion of the box-like bottom closure portion 18 which is glued or cemented thereto and provides a liquid tight association with the outer body portion.

It will be understood that the modified construction of container shown in Figs. 10 to 14, inclusive, embodies the same stable and durable construction as that of the container shown in Figs. 1 to 9, inclusive, and is likewise made waterproof by dipping in paraffin or equivalent wax-like materials; and may be packed in a carrier and utilized in a manner similar to the construction illustrated and described in connection with Figs. 1 to 9. Furthermore, the same advantageous results as to balance of construction and sanitation are also obtained with the modified container as with the container described in connection with Figs. 1 to 9, inclusive.

While we have shown the general body structure of the container as of rectangular form in the drawings, and have referred to its construction in the specification as being "rectangular" or "rectilinear", we do not limit ourselves to this form of construction, as we include within the meaning of the word "rectangular" or "recti-

linear" a container whose wall faces meet in angular form and preferably embodying one or more right angles.

Of course the container shown and described may be modified in various ways without departing from the invention herein set forth and hereafter claimed.

We claim:

1. A non-collapsible paper container comprising a multi-ply construction formed of rectangular body portions of substantially equal height sealed together into a unitary structure and having a strong multi-ply bottom structure composed of an inset piece having substantially V-shaped walls forming receptive grooves into which the bottom edges of one of the body portions are received to interlock and seal same in contact with the bottom edges of the body portion of the container, and also having upper flexible walls of lesser ply opening into the interior of the container, said flexible walls being creased slightly inward and folded upon themselves to provide a sealed closure, and a slideable spring-like sealing means for maintaining the overlapped edges of the flexible walls in sealed contact. 25

2. A non-collapsible paper container comprising a rectangular body composed of multi-ply paper wrappers, one of the rectangularly formed wrappers extending above the body and having its ends creased approximately from the corners thereof to the center of the edges and having its sides drawn together and vertically folded upon themselves to form a substantially V-shaped sealed pocket above the body. 30

3. A non-collapsible paper container comprising a rectangular body composed of multi-ply paper wrappers cemented together, one of the rectangularly formed wrappers extending above the body and having its ends creased approximately from the corners thereof to the center of the edges and having its sides drawn together and vertically folded upon themselves to form a substantially V-shaped sealed pocket above the body. 40

4. A non-collapsible paper container comprising a rectangular body composed of multi-ply paper wrappers, one of the rectangularly formed wrappers extending above the body and having its ends creased approximately from the corners thereof to the center of the edges and having its sides drawn together and vertically folded upon themselves to form a substantially V-shaped sealed pocket above the body, and a split tubular closing member for maintaining said fold. 45

5. A non-collapsible paper container comprising a rectangular body composed of multi-ply paper wrappers, one of the rectangularly formed wrappers extending above the body and having its ends creased approximately from the corners thereof to the center of the edges and having its sides drawn together and vertically folded upon themselves to form a substantially V-shaped sealed pocket above the body, and a coat of wax covering the entire structure. 55

6. A non-collapsible paper container comprising an inner rectangular tube, a bottom closure for same, a wrapper surrounding said tube and cemented thereto and having its ends extended beyond the ends of said tube, one of the extensions of said wrapper folded over the bottom closure, and the other extension having its ends creased approximately from the corners thereof to the center of the edges and having its sides vertically folded upon themselves to provide a sealed pocket above the body, and a split tubular 70

75 meaning of the word "rectangular" or "recti-

spring member adapted to slide over said closure to maintain same.

7. A non-collapsible paper container comprising multi-ply constructions formed of rectangular body portions of substantially equal height sealed together into a unitary structure and having a strong rectangular multi-ply bottom structure composed of an inset piece having substantially V-shaped edge walls forming receptive grooves into which the bottom edges of one of the body portions are received in sealed contact with the bottom edges of the body portion of the container, and also having upper flexible walls of lesser ply opening into the interior of the container, said flexible walls having their ends creased approximately from the corners thereof to the center of the edges and its sides drawn together and vertically folded upon themselves to form a substantially V-shaped sealed pocket above the body.

8. A non-collapsible paper container, comprising a multi-ply construction formed of rectangular body portions of substantially equal height sealed together into a unitary structure and having a strong rectangular multi-ply bottom structure composed of an inset piece interlocked and in sealed contact with the bottom edges of the body portions of the container, and also having upper flexible walls of lesser ply opening into the interior of the container, said flexible walls being creased slightly inward and folded vertically upon themselves to provide a sealed closure, a slideable spring-like sealing means for maintaining the overlapped edges of the flexible walls in sealed contact when the container is not in use, and a water-proof coating completely covering said container to prevent leakage and to assist in maintaining rigidity between the several parts.

9. A non-collapsible paper container, comprising a main body structure formed of multi-ply layers in its end walls and layers of at least two-ply in its side walls, said body structure extended to form single-ply upper flexible walls and lower single-ply portions adapted to overlap each other in the finished construction, and a single-ply

bottom structure the walls of which are interlocked between the bottom edge walls of the body structure and also having the lower extensions of the body structure overlapped and in sealed contact with the underside of the bottom structure; and wherein also, the upper flexible end walls are creased slightly inward to bring the side walls together, said side walls overlapped to provide a sealed closure for the container, and a slideable metallic spring-like sealing means is also provided for maintaining the overlapped walls in firm closed contact when the container is not in use, and wherein further, the paper container as a whole is water-proofed against leakage.

10. A non-collapsible paper container, comprising inner and outer body structure of substantially rectangular shape sealed together into a unitary construction and provided side walls having a plurality of layers and end walls overlapping each other at opposite sides to provide a more rigid construction and of greater ply than the side walls, said container extended at its upper part to form flexible upstanding single-ply walls, the upper ends of which are overlapped in sealed contact with each other but permitting the seal to be broken for providing an opening into the interior of the container when required, and also extended at its lower part to form extensions adapted to be folded and overlapped upon each other in permanent sealed contact, and an inset bottom portion in sealed and interlocked contact between the lower extensions and edges of the bottom walls of the container and providing a bottom closure having greater ply and rigidity than the side or end walls, and wherein also, the container is water-proofed throughout against leakage and provided with a slideable spring-like sealing means for the upper overlapped walls to temporarily seal the container when not in use.
